UNITED STATES PATENT OFFICE.

GEORGE C. SMITH, OF CHICAGO, ILLINOIS.

WATCH-CASE.

SPECIFICATION forming part of Letters Patent No. 371,282, dated October 11, 1887.

Application filed May 19, 1884. Serial No. 131,956. (Model.)

To all whom it may concern:

Be it known that I, GEORGE C. SMITH, a citizen of the United States, residing in Chicago, county of Cook, and State of Illinois, have invented certain new and useful Improvements in Watch-Cases, of which the following is a specification.

This invention relates to watch-cases in which the bezel or the bezel and the back is or are detachably secured to the "center" or body of the case.

Prior to my invention an internally-screw-threaded bezel has been fitted upon an externally-screw-threaded neck or annular flange formed with the center or body of the case, with which latter a back has also been detachably connected in a like way. A screw-threaded connection between either a back or a bezel and the center necessarily involves an extended frictional bearing between the two members, the extent of bearing-surface being proportional to the length of screw-thread, and hence in the event of either the bezel or the back being screwed down and wedged tight upon the center considerable difficulty will frequently be experienced in unscrewing and detaching the said members. While this defect could, to some extent, be remedied by providing the center with one or more short female screw-threads and providing the bezel or the back with one or more short male screw-threads or projections, yet such result would be attained at the expense of security in the connection between the said parts, it being evident that while the bezel or the back could in such instance be tightened upon or detached from the case quickly and by a slight partial rotation of either member, yet the limited bearing-surface would hardly be sufficient to prevent the detachable members from becoming accidentally detached or loosened, since the security of the connection between the detachable members and the center is dependent upon frictional contact, which is increased by reason of a binding force exerted in a direction perpendicular to the plane of the case, and consequently parallel with the opposing annular walls or sides of the detachable members and of the neck or flange on the center.

It is the object of my invention to provide a simple and effective temporary or detachable connection between a bezel or a back and

a watch-case center or body, which connection shall combine all of the advantages and avoid all of the disadvantages heretofore incident to the said long and short screw-threaded connection between said members. To such end I provide the center with one or more short inclined grooves or depressions adapted to receive one or more pins or projections on the back or bezel of both, which said grooves are formed to act as cams or wedges in the planes at right angles to each other, whereby, by applying the bezel or the back so as to cause its pins to enter the grooves in the center and then giving a partial rotation to either one of the said members, the pins or projections will in traversing the grooves draw the bezel or back down upon the center and cause a binding force to be exerted in planes at right angles to each other—one at right angles or perpendicular to the plane of either the back or face side of the case and the other in a line parallel to either of said planes—which said forces will increase in proportion to the extent to which the pins traverse the grooves.

In the drawings, Figure 1 is a plan view of the inner side of a bezel provided with pins adapted to enter the grooves or depressions in the case. Fig. 2 is a face view of a watch-case made in accordance with my invention. Fig. 3 is an edge view of the bezel, the center, and the back detached from one another. Fig. 4 is an enlarged detail showing a portion of the center and more clearly illustrating one of the grooves or depressions therein. Fig. 5 is a sectional view taken through one wall of the case with the back and bezel applied. Fig. 6 is a sectional detail taken on a plane parallel with the face of the case and on a line indicated by the dotted line α α , Fig. 4.

Referring by letter to the several figures of the annexed drawings, in which like letters denote like parts, A indicates the body or center of a watch-case which can be adapted either for an open-faced or a hunting-case watch, as may be desired. In the present illustration the bezel B and the back C are both adapted to be detachably connected with the center; and to such end the center is provided at each side with a neck or annular flange, α , in which are formed the grooves or depressions for receiving the pins or projections on the detachable bezel and back.

Each one of the grooves or depressions D is formed in the outer side of one of the annular flanges a of the center and inclines from the base to the edge of the flange, at which latter 5 point the groove terminates in a notch, D', constituting an entrance to the inclined portion of the groove, and hence forming a part of the same. Under this arrangement the groove runs at an angle to the plane of either 10 side of the case, and is inclined with relation to an annular seat, a', formed at the base of the flange, upon which said seat either the bezel or the back, as the case may be, can be drawn and seated after the pin on the back or 15 bezel has been fitted in the groove and the said member turned to the required extent upon the center.

The groove or depression is made deepest at its end in the edge of the flange where the 20 pin enters, and from this point, which may be called its "outer end," the groove grows gradually shallower or decreases in depth as it approaches the annular seat or middle portion of the body of the case, whereby the groove is 25 finally lost at its inner end. In this way the back wall, d', of the groove will be eccentric to the annular wall a' of the flange or neck, or to the circumference of the watch-case. The center can be provided with one or more of 30 these grooves for a corresponding number of pins, E, on the bezel, and with one or more like grooves for a like number of pins on the removable back, it being preferable, however, to provide two grooves and a corresponding 35 number of pins for each one of said detachable members.

After the bezel or back is placed in such position on the center that its pins shall enter the grooves through the notches or entrances 40 constituting lateral continuations of the deeper end portions of the grooves, the back or bezel can be secured upon the center by holding one member and giving a partial rotation to the other, during which operation, supposing the 45 center to be held stationary and the movable member to be turned, the pin traversing the grooves or depressions will, in approaching the annular seat a', draw the moving member down upon the said seat, while at the same 50 time the pins, in approaching the shallower portions of the grooves or depressions, will bind against the back wall of the latter with a force increasing in proportion to the extent to which the movable member is turned upon the center, 55 and in a direction parallel with the plane of the center or face of the watch and at right angles to the wall of the annular flange or neck about which the movable member is turning. In this way, with but a short groove, I obtain 60 a binding force in two directions, the one serving to bind on the annular seat, owing to the inclination of the groove with relation to the latter, and the other serving to cause the outer end of the pins to bind against the back walls 65 of the grooves or depressions, owing to eccentric relation which the said walls bear to the

annular outer wall of the flange or neck in which the said grooves or depressions are formed.

It will be understood that either the back or 70 the bezel, or both, can be thus detachably connected with the case, and that the grooves could be formed in the back and bezel and the pins or projections arranged on the case; hence I do not limit myself to the precise arrangement shown, but regard my invention 75 as embodying either of said arrangements.

In an application, Serial No. 114,031, I have shown cams or flanges projecting beyond the periphery of the rim of the center and a bezel 80 provided with lugs, which bezel and lugs engage with said cams to lock the center and bezel, and I therefore make no claims to the aforesaid construction in this application.

Having described my invention, what I 85 claim, and desire to secure by Letters Patent, is—

1. The combination, in a watch-case, of a detachable member thereof removably secured in position by a connection consisting of one 90 or more projections on one of the parts and one or more grooves or depressions formed in the remaining part of the case and adapted to receive the said projections, which groove or grooves are inclined with relation to the planes 95 of either the front or rear sides of the case and formed with their back walls eccentric to the circumference of the latter, whereby said detachable member is simultaneously tightened on both the seat and laterally on the flange or 100 riser, substantially as described.

2. The combination, in a watch-case, of a detachable member thereof removably secured in position by a connection consisting of one or more projections on one of the parts and one 105 or more grooves or depressions formed in the remaining member and adapted to receive the said projections, these grooves being inclined with respect to the planes of either the front or rear, of a gradually-decreasing depth from 110 the points at which the pins enter the grooves when the parts are fitted together, substantially as described.

3. A watch-case center having at one or both of its sides an annular flange provided 115 with one or more inclined grooves or depressions commencing at the edge of the flange and decreasing in depth as they approach the base of the latter, in combination with a detachable back or bezel provided with a projection or projections adapted to enter the groove or grooves in the flange, substantially 120 as and for the purpose described.

4. A watch-case center provided with a grooved flange, in combination with a detachable back or bezel having a projection adapted 125 to enter the groove in the flange of the center, said groove being formed and arranged so that when the back or bezel is turned on the center with the pin received in the groove the walls 130 of the latter shall cause a binding force to be exerted between said members in two direc-

tions, one parallel with and the other at right angles to the plane of either the back or face side of the case, substantially as set forth.

5. A watch-case center provided at one or both sides with an annular seat, a' , a flange rising from said seat, and an inclined groove, D , formed in said flange, substantially as described, in combination with a back or bezel,

or both, provided with one or more pins adapted to enter said groove, substantially as set forth.
